BASE FOR SWIVEL CHAIRS

**Tom Elleman, Port Washington, Wis., assignor,
by mesne assignments, to The Seng Company,
Chicago, Ill., a corporation of Illinois**

Application December 23, 1944, Serial No. 569,522

2 Claims. (Cl. 248—194)

1

This invention relates to an improvement in bases for swivel chairs, particularly to the hub which holds the legs of the base together and provides the support for the chair iron spindle.

One of the objects of this invention is to provide a hub which grips the wooden legs with a continual pressure even when changes occur in their thickness, and also provides a bearing for the spindle which will permit the spindle to rotate readily and withstand wear.

Another object of the invention is to provide a hub in which the spindle is vertically adjustable by means requiring a minimum amount of space between the chair spider and the top of the hub.

These objects are obtained by forming the hub from leg brackets made from steel stampings held in semi-flexible relationship to a cast iron sleeve or tube and supporting the chair iron spindle within the cast iron sleeve. The cast iron sleeve or tube provides an excellent bearing for the spindle even when lubrication is not present, as the surface characteristics of cast iron, probably due to its high carbon content, are such as to reduce friction to a minimum and increase the life of the hub and spindle. However, to make the hub completely of cast iron would unduly increase weight and not provide the advantages arising from the use of leg brackets formed of steel stampings. These leg brackets which are secured to the cast iron sleeve in such a way as to permit them to flex along most of their leg-engaging portion provide a continuous holding pressure even though the thickness of the wooden leg may alter due to manufacturing errors and differences in climatic conditions to which the wood is subjected. The necessary space between the chair iron mounted on the spindle and the top of the hub required for the adjusting hand wheel is kept to a minimum by providing a flange on the top plate of the hub, a hand wheel which has a downwardly depending flange enclosing the flange on the hub, a key washer between the hand wheel and the top of the hub, and a screw in the downwardly depending flange to fit under the flange on the hub. This lessening of the required distance between the chair iron and the top of the hub makes it possible to provide a hand wheel which has a greater length of thread and also permits an additional lowering of the chair seat relative to the base.

With the foregoing and other objects in view, developed by the following description, the invention consists in certain novel advantageous structural organizations and features, as well as

2

combinations and sub-combinations, as more fully explained hereinafter and specified in the following claims.

Referring to the accompanying drawing forming a part hereof, Figure 1 is a fragmentary view partly in side elevation and partly in vertical section of a chair hub embodying the present invention, part of one of the legs being broken away for the sake of clarity in illustration;

10 Figure 2 is a view taken on the line 2—2 of Figure 1 with the hand wheel removed for the sake of clarity in disclosure;

Figure 3 is a fragmentary sectional view taken on the line 3—3 of Figure 1;

15 Figure 4 is a fragmentary sectional view taken on the line 4—4 of Figure 3; and

Figure 5 is a bottom plan view of the hub viewed in Figure 1 with the legs and hand wheel removed and with a part broken away for the purpose of clarity in illustration.

Referring in greater detail to the drawings, there is shown a hub for the base of swivel chairs, designated as a whole at 1. It is secured to the wooden legs 2 of the chair base as hereinafter described. The hub 1, rotatably supports the spindle 3 of the chair iron. To this spindle is secured the chair iron (not shown) for holding the chair seat. The hub 1 as a whole comprises two main parts: the supporting or hub portion 30 per se; and the hand wheel or vertical adjusting means. The hub per se comprises a central cast iron sleeve or tube 6 and leg engaging brackets 9. The cast iron sleeve 6 has at its upper end an outwardly extending flange 10 which forms the bearing for the vertical thrust imposed by the spindle 3 and the support for the top plate 7. Adjacent the bottom of the sleeve 6 there is another outwardly extending flange 11 which forms a shoulder for the washer 8a.

40 The top plate 7 has a central aperture into which the top portion of the sleeve 6 is press-fitted to form a tight juncture therebetween. The top plate 7 has an upwardly and outwardly curved flange 12 providing one of the abutting means between the hub and the hand wheel to prevent separation while permitting relative rotation therebetween. The top plate 7 has equally angularly spaced screw receiving apertures 16 whereby it may be securely fastened to the wooden legs 2. The leg brackets or side pieces 9 are each of similar construction and are somewhat U-shaped in cross section. At the spaced intervals along each leg bracket there are provided ribs or bosses 14 pressed outwardly therefrom to stiffen and strengthen the arms of the bracket.

The leg brackets are positioned at four equally-spaced angular places about the tube 6 and the legs 2 are received between the opposing side arms of adjacent leg brackets. Fish-tail lugs 15 are provided at the top of each arm of the leg brackets 9. They fit through rectangularly-shaped openings provided in the top plate 7 as is shown in Figure 2 and are spread as illustrated to form a rigid connection between the brackets and the top plate. Slots 9a are provided in the central portion of the bottoms of the brackets 9 to receive radially-extending wings or ears 13 formed on the washer 8b. After the leg brackets 9 have been secured to the top plate 7, a washer 8a is press-fitted over the bottom of the tube 6 and fits snugly against the shoulder formed by the lower flange 11. This washer is provided with four flat portions which engage with the lower central portion of each leg bracket 9 to properly position those flanges and hold them from moving inwardly toward the sleeve 6. Thereupon, a washer 8b provided with radially-extending wings or ears 13 is press fitted on the lower end of the tube 6 with the wings extending in the slots 9a. The ends of the wings 13 are then formed upwardly as shown in Figure 1 to grip and hold the bottoms of the leg brackets securely in place with respect to the sleeve 6.

This method of securing the leg brackets provides for a rigid attachment relative to the sleeve 6 but permits relative movement between the lower portions of the side arms of the leg brackets, thus making those arms free to flex throughout a substantial portion of their length. As the legs 2 are forced in between the side arms of the leg brackets, they will elastically deform these brackets and cause them to be placed under stress thereby forming a continuous pressure between the leg brackets and each leg, even though the thickness of the legs subsequently changes as the result of partial drying due to climatic conditions. The stress imposed upon the brackets during the assembly process will be sufficient to maintain such continuous pressure even when changes in thicknesses of leg thereafter occur. Because of the flexibility of the leg brackets, slight variances in the thicknesses of the legs used in the assembly of the chair base will not cause manufacturing difficulties. The flex will give sufficiently to accommodate oversize legs. As an added protection in maintaining the legs rigidly in place, screws 16a may be inserted through the openings 16 into the wooden legs 2.

The spindle 3 is rotatably held within the central longitudinal aperture in the cast iron sleeve 6 and is guided thereby. In order to permit adjustment of the spindle 3 vertically relative to the sleeve 6, the spindle is provided with a standard thread upon which is threaded a nut or hand wheel 20. The hand wheel 20 has a central hub 21 and a downwardly-extending flange 27 which extends over the upwardly and outwardly-extending flange 12 of the top plate 7. The bottom of the hub 21 is provided with radially-extending depressions 26. A key washer 22 has similarly-shaped projections which coincide with and fit into the depressions 26 to prevent the wheel 20 from turning with respect to the washer 22 unless additional turning pressure is manually exerted on the hand wheel 20. The key washer 70

22 has a tab 23 which rides in a key way 24 extending vertically through the threaded portion of the spindle 3. This causes the key washer to be fixed against relative rotation with respect to spindle 3. Thus the thrust placed on the spindle 3 is transferred through the hub 21 and key washer 22 to the top of the cast iron sleeve 6. As the chair iron is swivelled, the spindle 3, key washer 22, and hand wheel 20 are rotated together, and no vertical adjustment is attained. When the weight of the occupant of the chair seat is removed, the hand wheel 20 may be manually rotated with respect to the spindle 3, thus raising or lowering it with respect to the spindle 15 3 to adjust the height of the chair seat.

Although only one embodiment of the invention is shown and described herein, it will be understood that this application is intended to cover such changes or modifications as come 20 within the spirit of the invention or scope of the following claims.

I claim:

1. A hub for a chair base comprising: a cast iron sleeve adapted to receive and rotatably support a chair iron spindle, said sleeve having a flange at its upper end and a flat bottomed shoulder adjacent its lower end; a top plate abutting the underside of said flange and having a press fit on said sleeve; stamped sheet metal leg 25 brackets having upright leg engaging side arms secured to said top plate to anchor said brackets; and means secured to the sleeve in abutting relationship to the flat bottom of said shoulder to secure the lower ends of the leg brackets in 30 spaced relation to the sleeve while leaving the leg engaging side arms free to flex.

2. A hub according to claim 1 wherein the means to secure the lower ends of the leg brackets comprises a spacing washer abutting the shoulder and engaged with the leg brackets to hold them spaced from the sleeve, and a securing washer press fitted on the sleeve in abutting relationship to the spacing washer, said securing washer having ears engaging the bottoms 40 of the leg brackets to hold them inwardly against the spacing washer.
